UNITED STATES PATENT OFFICE

SCOTT C. BARTHOLOMEW, OF PITTSBURGH, PENNSYLVANIA, ASSIGNOR, BY MESNE ASSIGNMENTS, TO REMINGTON RAND INC., OF NEW YORK, N. Y., A CORPORATION OF DELAWARE

STOPPING DEVICE FOR CARD-FEEDING MACHINES

Application filed March 27, 1926. Serial No. 97,920.

The present invention relates to statistical machines operated by perforated cards and more particularly to a device for automatically stopping a machine when a card fails to feed in the proper manner.

In the operation of card sorting machines or other machines wherein a succession of cards are fed along a common path of travel, it frequently happens that a card sticks on account of a bent edge or corner or for some other reason fails to feed properly and as a result a dozen or more cards often pile up before it is possible to manually stop the machine. The cards thus caught by the failure of one card to feed are so bent and damaged that they cannot be used again and new cards must be punched to replace them, all of which causes a considerable loss of time and a corresponding lessening of the output.

Some of the objects of the present invention are to provide a means for automatically stopping a card feeding mechanism in case a card sticks or otherwise fails to feed properly; to provide a device whereby the damage of cards through a failure to feed properly through a sorting machine or other statistical machine is reduced to a minimum; to provide a means for eliminating loss of time caused by cards damaged in the feeding mechanism; to provide a device for more nearly approximating a constant card output than has heretofore been possible; and to provide other improvements as will hereinafter appear.

In the accompanying drawings Fig. 1 represents a schematic elevation of a card feeding mechanism equipped with one form of the present invention; Fig. 2 represents a front elevation, broken away, of one form of automatic stopping control mechanism; Fig. 3 represents a section on line 3—3 of Fig. 2; Fig. 4 represents a section on line 4—4 of Fig. 3, and Fig. 5 represents a detail in perspective of the circuit closing devices and associated parts.

Referring to the drawings, one form of the present invention is shown in Fig. 1 as applied to the card feeding mechanism of a sorting machine, though the invention is not specifically so limited, and the card magazine 10

is diagrammatically illustrated to deliver a succession of cards to an analyzing unit 11 from which each card enters a path of travel formed by pairs of rollers 12 and 13 in order to be fed to the respective receptacles which are to receive the cards. In this type of machine shutters 14 are located adjacent the pairs of feed rollers and in such a position that any shutter selected by a card will be automatically thrown into the path of that card and deflect it into the receptacle predetermined by a card perforation. In the present instance, the sorting machine is operated electrically and the control for stopping it is interposed in the circuit of the operating motor 55 at a break in the conducting wires 15.

As here shown the conducting wires 15 are respectively connected to binding posts 16 which are supported by a strip of insulation 17 and terminate in contact heads 18 at the opposite side of a plate 20 upon which the insulation strip 17 is supported. These contact heads 18 are respectively arranged to be engaged by faces 21 of two interconnected spring contactors 22 laterally projecting from a strip of insulation 23. This strip 23 is carried by a pin 24 which is axially slid able in the walls of the casing 25 and also may have a limited rotary motion. A hand knob 26 on the one projecting end of the pin 24 allows the latter to be reset so that the contactors 22 are in contact with the contacts 18 in order to supply current to the motor of the machine to which the device is applied. The aforesaid rotary movement of the pin 24 is limited by 70 the position of a guide block 29 arranged in the path of the insulating strip 23 and serving also as a guide for the latter.

For the purpose of shifting the pin 24 axially with an accompanying turning movement, it is provided with an arm 27 which projects laterally from the pin and has its free end connected to a coil spring 28, the other end of which is connected to a fixed eye 90 30 so located as to maintain the spring 28 under tension and exerting an upward and lateral pull upon the arm 27. The arm 27 is formed on a plate which overlies and supports the strip of insulation 23, and is secured to the pin 24 by screws. Thus, when the pin 24 is 95 100

free to move the spring 28 will swing the arm 27 in a direction to rotate the pin 24 and simultaneously lift the pin a sufficient distance to remove the contactors 22 from the contacts 18. This tension of the spring 28 also serves to hold the contactors 22 against the contacts 18 with good contact pressure when the circuit of the motor is to be maintained closed.

10 As a means for holding the pin 24 in its circuit closing position, it is provided with a lug or catch 31 which is positioned to be engaged by a hook latch 32 which is suitably pivoted at 33 to a part to the rear wall 15 of the casing 25 and provided with a bearing for the pin 24, while a coil spring 34 is stretched between a fixed pin 35 and the opposite end of the latch 32 so that the latch normally tends to swing over the catch 31 and thus hold the pin 24 against movement.

10 The latch 32 is normally positioned to hold the pin 24 closing the operating circuit and the release of this latch is arranged to be effected by the failure of a card or cards to 25 properly feed along their path of travel. One means for controlling such release of the latch 32 comprises a wire or equivalent device 36 which is connected at one end to the projecting end of the latch 32 and is located 30 parallel to the path of travel of the cards and extends through all of the pairs of feed rolls 12 and 13 where its outer end joins a tension device. In the present instance this device consists of a threaded pin 38 traversing a slot 40 in a fixed bracket 41 and has a thumb nut 42 abutting the outer face of the bracket 41. In this way the wire 36 is maintained under proper tension, stretched in 35 close proximity to the upper sides of the cards, so that any deflection of a card as it passes along beneath the wire 36 is constantly transmitted to the wire 36 and the movement thereof under such deflection is sufficient to exert the necessary pull to release 40 the latch 32 from the catch 31 and thus place the pin 24 under control of the spring 28. When this occurs, the tension of the spring 28 swings the arm 27 laterally and upward so that the contactors 22 are moved 45 from the contacts 18 and the circuit of the motor which is driving the sorting machine is broken and the latter immediately stops.

From the foregoing it will be apparent that a complete unitary stop mechanism has been provided which is sensitive to any variation of a card or cards from the proper path of travel to cause a misfeed or clogging of the feeding mechanism, and which acts in a positive manner to stop the feed before 50 damage is done to the cards. This construction not only prevents mutilation of cards during the sorting or other operation but increases the production of the machine in a given time while resulting in a substantially 55 constant operation.

Having thus described my invention, I claim:

1. In a machine of the character stated, the combination of a mechanism for feeding cards successively along a common path, a control for said mechanism, and means, including a wire stretched along said path to be engaged by a card distorted from said path, for stopping said feeding mechanism. 70

2. In a machine of the character stated, the combination of a mechanism for feeding cards successively along a common path, electric means for operating said mechanism, a switch for controlling said electric means, means normally holding said switch to close the circuit to said electric means, and means actuated by a card distorted from said path for opening said switch to stop said feeding mechanism. 75

3. In a machine of the character stated, the combination of a mechanism for feeding cards successively along a common path, means including an electric circuit for controlling said feeding mechanism, a switch in said circuit, means including a spring latch for locking said switch to close said circuit, and a wire stretched along said path and connected to said latch, whereby a card distorted from said path moves said wire to release said latch. 80

4. In a machine of the character stated, the combination of a mechanism for feeding cards successively along a common path, means including an electric circuit for controlling said feeding mechanism, a contact forming one terminal of said circuit, a contactor forming another terminal of said circuit, a spring actuated pin mounting said contactor, a latch for locking said pin in position to press said contactor against said contact, and means stretched along said card path and connected to said latch to release said pin by the action of a card distorted out of said path. 100

5. The combination with means for feeding cards along a common path to a plurality of card receptacles, of means adapted to be operated by a card deflected at any point in said path for stopping feeding of said cards. 110

6. The combination with means for feeding cards to a plurality of receptacles, of means extending along said path and adapted to be operated by cards deflected at any point of their travel to any receptacle for stopping feeding of said cards. 120

7. The combination with means for feeding cards to a plurality of receptacles, of common means actuatable by any card at any point of its travel to any receptacle for stopping feeding of the cards. 125

Signed at Pittsburgh, county of Allegheny, State of Pennsylvania, this 11 day of March, 1926.

SCOTT C. BARTHOLOMEW. 130
